US00D900747S

(12) **United States Design Patent** (10) **Patent No.:** **US D900,747 S**
(45) **Date of Patent:** **** Nov. 3, 2020**

(54) **UNIVERSAL TRAVEL ADAPTER**

(71) Applicant: **DONGGUAN WONTRAVEL ELECTRIC CO., LTD.**, Dongguan, Guangdong (CN)

(72) Inventor: **Shuyan Huang**, Dongguan (CN)

(73) Assignee: **DONGGUAN WONTRAVEL ELECTRIC CO., LTD.**, Dongguan, Guangdong Province (CN)

(**) Term: **15 Years**

(21) Appl. No.: **29/696,873**

(22) Filed: **Jul. 2, 2019**

(51) **LOC (12) Cl.** **13-03**

(52) **U.S. Cl.**

USPC **D13/137.2**

(57) **CLAIM**

The ornamental design for a universal travel adapter, as shown and described.

DESCRIPTION

FIG. 1 is a front, top and right perspective view of a universal travel adapter showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is a rear, bottom and left perspective view thereof with an Europlug being extracted from a housing thereof. The broken lines depict portions of the universal travel adapter in which the design is embodied that form no part of the claimed design.

1 Claim, 8 Drawing Sheets
